CLAIM

The ornamental design for a display screen or portion thereof with graphical user interface for analyte data presentation, substantially as shown and described.

DESCRIPTION

The file of this patent contains at least one drawing executed in color. Copies of this patent with color drawings will be provided by the Office upon request and payment of the necessary fee.

FIG. 1 is a front view of a display screen or portion thereof with graphical user interface for analyte data presentation that incorporates the new, original, and ornamental design; FIG. 2 is a second embodiment thereof;

FIG. 3 is a third embodiment thereof;

FIG. 4 is a fourth embodiment thereof;

FIG. 5 is a fifth embodiment thereof; and,

FIG. 6 is a sixth embodiment thereof.

The broken lines showing a display screen form no part of the claimed design.
